COMBINED HOLDER AND MOUNTING BRACKET
FOR SOLID DEODORANT, PERFUME, INSECT
REPELLANT OR THE LIKE

Georg Schimanski, Hagen, Germany, assignor to Global Werk GmbH

Filed Oct. 15, 1975, Ser. No. 622,630

Claims priority, application Germany Apr. 21, 1975

Term of patent 14 years

Int. Cl. D23—04

U.S. Cl. D23—150

Fig.1

Fig.3

FIG. 1 is a front perspective view of a combined holder and mounting bracket for solid deodorant, perfume, insect repellant or the like showing my new design;

FIG. 2 is a fragmentary rear perspective view thereof, with the mounting bracket omitted for ease of illustration;

FIG. 3 is a perspective view of the mounting bracket, with the holder omitted for clarity of illustration; and

FIG. 4 is a side elevational view thereof, taken in the direction of line IV—IV in FIG. 1.

I claim:

The ornamental design for a combined holder and mounting bracket for solid deodorant, perfume, insect repellant or the like, as shown.
